Attorney

UNITED STATES PATENT OFFICE.

JAMES M. STRAUB, OF PITTSBURGH, PENNSYLVANIA, ASSIGNOR TO ELECTRIC WELDING COMPANY, OF PITTSBURGH, PENNSYLVANIA, A CORPORATION OF PENNSYLVANIA.

CONCRETE REINFORCEMENT.

Application filed December 21, 1926 Serial No. 156,098.

My invention refers to improvements in concrete reenforcement, and relates particularly to means for reenforcing the concrete adjacent to or surrounding a beam, column, 5 or other structural member. The practice of concrete reenforcement is well established and understood by those skilled in the art, and many and various forms of the same general kind are known and used, as shown by 10 patents of Reed #1,166,545 and Masten #1,304,586.

The objects in view in the present invention are to provide a simple and efficient form 15 of clip formed of a wire or rod, bent at certain predetermined points alternately in opposite directions, without closed looping, for surrounding engagement with a structural beam, column, or the like.

The clip is generally U-shaped, bent at the 20 end or at each side to provide two spaced apart inwardly extending bearing projections for contact with the beam or column flanges, corner open sided loops, and an intervening outwardly spaced reenforcing bar 25 or strand, with freely extended ends for holding engagement with the structural member.

Certain preferred embodiments of the invention are shown in the accompanying drawings, in which:

30 Fig. 1 is a perspective view showing the device as applied to a beam;

Fig. 2 is a similar view showing the relative arrangement of a plurality of the clips, with their supported reenforcing members;

35 Fig. 3 is a plan view, showing the application of the clip to a column;

Fig. 4 is a similar view showing a modified construction;

40 Fig. 5 is a perspective view further showing the application to a column, in alternating side placement;

Fig. 6 is a view similar to Fig. 3, showing a modified construction.

The structural member, of I-beam, channel, 45 or other similar or compound forms, is usually provided with a web 2 and flanges 3.

The clip member is formed of a rod or wire having parallel sides 4 of suitable length for binding around or over the flanges, with a 50 cross connecting member 5 having inwardly bent open loops or reversed bends 6. These are preferably located adjacent the side

members 4 which are bent inwardly, as at 7, forming outwardly bent open loops on the same general plane as connecting member 7. 55

As thus made the clip is adapted to be placed around the beam, embracing it at each side, so that the free ends may be bent over the outside of the upper flanges, for 60 secure attachment, as in Fig. 1. In such position the inwardly deflected shoulders 6 bear against the outer face of the opposite flanges, spacing the cross arm 5 and the open loops 7 outwardly from contact, and in projecting 65 location for encompassing embodiment in adjacent surrounding concrete A, as shown.

By such arrangement the open loops 7 provide projecting stirrup supports for loosely placed longitudinal reenforcing strand members, as wires or rods 8. These latter are also 70 supported in such manner materially below the lower face of the beam, for complete immersion and imbedding in the concrete, away from the beams. Such longitudinal strands or rods, being at the corner portions of the 75 structural member, tend to avoid cracking of the concrete at such locations.

In making the clip for use on a column, as in Fig. 3, the end connecting cross member 9 is preferably straight, as shown, for bridging 80 across the edges of the flanges 3, leaving ample space for the surrounding concrete A.

The side members 4' in such case are bent inwardly, as at 6', with the outwardly spaced connecting arm 5', similar to the construction already described. When the free ends of the strands 4' are bent around the column in opposite directions, open loops 7' like loops 7 are provided, one at each corner, for placement of the longitudinal vertical reenforcing strands 8'. These may be tied in place by light wiring or otherwise, if desired. 90

The clips are preferably applied from alternately opposite sides to the column for better averaging the strain resisting reenforcement throughout the length of the column. 95

If desired, the free arms of the clips may be sufficiently long to bend entirely around the opposite side of the beam or column, as 100 indicated in Figs. 1 and 3, or they may be made shorter, for clinching attachment around the adjacent flanges, as in Figs. 4 and 5.

The clip may also be provided with comparatively short arms for clinching attachment around the ends of the flanges, as in Fig. 6, with the same general effect, but limited as to its zone of reenforcement.

With either method of attachment the clips may be easily applied and held in place and will not only provide ample projecting anchoring elements for the concrete, but also ensure the supporting and holding placement of the longitudinal strands outwardly from the structural member.

It will also be observed that the cross arm 5 or 5' may be used as a support or brace 15 for additional longitudinal members 8 or 8', should such be desired.

The advantages of the construction will be readily understood and appreciated by all those accustomed to the use of concrete reenforcement.

The clips are easily and cheaply formed of straight rods or wire, and are capable of compact packing, shipment or storage. They may be located at any desired spacing distance apart, and are readily adapted to quick 25 application and use in the manner described.

They may be made of any suitable size, gauge or weight to suit the conditions of use, and have proved to be highly efficient in the art.

What I claim is:

1. A reenforcing clip for concrete construction consisting of a continuous single member rod bent to provide parallel side arms and acute angle inwardly open corner loop portions providing bearing abutments for contact against a structural member and open recesses for reenforcing members laid longitudinally of the structural member.

2. A reenforcing clip for concrete construction consisting of a continuous single member rod bent to provide parallel side arms and acute angle inwardly open corner loop portions providing bearing abutments for contact against a structural member and open recesses for reenforcing members laid longitudinally of the structural member and a cross connecting strand member spaced outwardly beyond the bearing abutments.

In testimony whereof I hereunto affix my signature.

JAMES M. STRAUB.
